UNITED STATES PATENT OFFICE.

JOHN G. ENGELHART, OF ATLANTA, GEORGIA.

FURNACE.

1,135,169.

Specification of Letter Patent. Patented Apr. 13, 1915.

Application filed August 4, 1911. Serial No. 642,359.

To all whom it may concern:

Be it known that I, JOHN G. ENGELHART, a citizen of the United States, residing at Atlanta, in the county of Fulton and State 5 of Georgia, have invented certain new and useful Improvements in Furnaces, of which the following is a specification.

This invention relates to furnaces, and more particularly to means for providing an 10 effective circulation of air about the fuel in the fire pot.

In the patent issued to me December 29, 1908, No. 908,228, means for affording circulation within the base are shown, and in the 15 present instance I provide air conducting devices for supporting the grate bars and other portions of the structure and for admitting air from the base to air tubes on the sides of the fire pot and attached to or 20 formed integrally with the boiler sections. I may also, if desired, provide air conducting devices below the front section of the furnace, at the grate level, and designed to admit air from the base to an air space 25 within the said front section, and so arranged that the aforesaid devices assist in supporting the front section.

In the accompanying drawings forming part of this application, Figure 1 is a perspective view of a portion of the furnace structure, with parts broken away. Fig. 2 is a top plan view of two of the air conducting devices which are also employed as grate bar supporting means. Fig. 3 is an 35 elevation of the devices shown in Fig. 2. Fig. 4 is an end view thereof. Fig. 5 is an enlarged view in vertical section on line 5—5 of Fig. 1 showing one of the air conducting devices located below the front section or wall of the furnace. Fig. 6 is a section on the line 6—6 of Fig. 7. Fig. 7 is a section on the line 7—7 of Fig. 6.

In carrying out my invention, I make use of a hollow base portion 10, above which 45 the boiler sections are mounted, the sections 15 at the rear of the fire pot having a series of vertically arranged hollow members or pipes 16 connecting the lower transverse pipes 17 with the upper transverse pipes 18. 50 The fire pot sections 19 are substantially U shaped and have no intervening vertical pipes between those constituting the sides. The rear boiler section may have an enlarged pipe or chamber at its upper portion, 55 as at 21, and a lower transverse pipe 22, an opening 23 being provided for the escape

of the products of combustion. The front section 25 of the structure has an upper chamber 26, similar to water chamber 21, and a lower transverse pipe 27, providing an 60 opening 29 closed by door 29'. A clinker door 30 and a door 31 opening into the base are located as shown in Fig. 1. Each of the vertical pipes of the section immediately at the rear of the fire pot is provided with a 65 baffle plate 35, reducing the air space between the lower portions of these vertical pipes and directing the currents of heated air and gases upwardly before they pass downwardly in order to escape through the 70 opening in the rear section of the boiler. Air tubes 37 are located alongside of the baffle plates and convey air from the hollow base to the fire pot and discharge over and into the mass of burning fuel. The tubes 75 are provided with elongated openings 38 as shown. At the rear of the fire box is a stationary grate member 41 and between the latter and the stationary grate members at the front of the fire box (described below) 80 are the movable grate bars 42, the latter being provided with trunnions 43 supported in sockets formed on the edges of the devices 44. The devices last mentioned constitute an important part of the structure 85 here described and serve to support the grate bars and to provide means for admitting air from the base 10 to the vertical air tubes 45 on the inner walls of fire pot sections 19. The grate bar supports include 90 box-like members 46 which are secured by bolts 47 passing through the downwardly projecting members or plates 48 and through a portion 49 of the base. The sockets for the trunnions 43 are indicated by 50, one-half of each socket being formed in the free 95 corners of each supporting device 44. The front face of the latter is formed as at 44'. A supporting device similarly formed may be used below the front section of the furnace.

Referring to Fig. 5 which is a section on line 5—5 of Fig. 1, it will be noted that the front section has an air space 51 in the rear of the water space or chamber 52, space 51 105 communicating with the interior of the fire pot by means of openings 53. One of these spaces is located on each side of the door 30. Ribs 54 are formed on the wall between openings 53 and serve to keep the fuel from 110 obstructing the passage of air.

It will be observed that the inner walls 55

and 56 of those stationary devices 44 which are used below the front furnace section are substantially on a line with the walls 57 and 58 of the air chamber of the front section, 5 the latter being supported largely on devices 44 but in part also on base 10.

Particular attention is directed to the effective means for distributing the air about the fire pot and the fuel therein, and for 10 directing the heated gases rearwardly from the fire pot between the vertical pipes of the boiler sections there located.

What I claim as new and desire to secure by Letters Patent is:

15 In a device of the class described, a furnace structure including a fire box, one wall of which comprises an upper hollow portion and a lower hollow portion of less thickness than the upper portion, a stationary grate 20 member having an air conducting space con-

nected with the lower portion of the furnace structure and including a member located below the thinner portion of the wall and substantially coincident with the inner face thereof, and a member located beneath the 25 thicker portion of the wall, an apertured plate extending from the member last mentioned and substantially in line with the inner surface of the aforesaid thicker portion, said apertured plate defining with the 30 remainder of the wall an air space partly inclosed by the upper and lower hollow portions.

In testimony whereof I affix my signature in presence of two witnesses.

JOHN G. ENGELHART.
